RADIO RECEIVING SYSTEM

Ben J. Chromy, Hopkins, Minn.

Application April 11, 1930, Serial No. 443,564

8 Claims. (Cl. 250—11)

This invention relates to radio receiving systems in general. More specifically this invention relates to directional radio receiving systems employed for guiding moving vessels.

5 An object of this invention is to provide a receiving system for successively controlling the energization of alarms or visual indicators in accordance with signaling energy intercepted by antennæ having maximum field strengths in different directions.

10 Another object of this invention is to provide a receiving system for successively controlling the energization of windings of a relay in accordance with signaling energy intercepted by directional antennæ having maximum field strengths in different directions.

15 Still another object of this invention is to provide a system for guiding moving vessels, such as aeroplanes, consisting of a plurality of directional antennæ arranged to be successively coupled in predetermined order to an amplifying system with which is associated a relay provided with a plurality of windings, selected ones of these windings being arranged to be energized in accordance with signaling energy intercepted by selected ones of the directional antennæ.

20 Other and further features of this invention will be apparent to those skilled in the art to which it pertains from the following specification.

25 This invention is an improvement over that disclosed in my copending application Serial Number 433,912, filed March 7, 1930, for radio receiving systems. In accordance with this invention, a plurality of directional antennæ are arranged to be successively coupled to the input circuit of an amplifier system. These directional antennæ or antenna arrays are adjusted to receive signaling energy of the proper phase relation from directions slightly displaced from one another. The angle of displacement may be 30 somewhat in excess of 90° or even less than 90° in cases where two directional antenna arrays are employed, but in cases where three antennæ arrays are used the angle of displacement should be less than 90° between adjacent antennæ. The 35 output stage of the amplifier system is arranged to energize a plurality of windings of a relay arrangement. Each of the effective windings of the relay arrangement is connected into the anode circuit of an electron discharge device. The potential of the source of current supply for these anode circuits is periodically varied and simultaneously the coupling between the input circuit of the amplifier system and successive 40 ones of the antenna arrays increased and de-

creased. The result thus obtained is that a certain one of the relay windings is energized in accordance with signaling energy intercepted by a certain one of the antenna arrays. The relay winding corresponding to the antenna array intercepting signaling energy of the greatest magnitude is energized through the operation of the amplifier system and functions to control the circuit of a selected indicator. By observing the indicators, which are preferably incandescent lamps, the operator is constantly informed which of the antenna arrays intercept signaling energy of the greatest magnitude in the proper phase relation and whether or not the vessel which he is piloting is proceeding in the proper predetermined course.

5 This invention will be more completely understood from the accompanying drawings, in which, briefly:

10 Fig. 1 illustrates the circuit diagram of one form of this invention;

Fig. 2 illustrates a modified form of this invention;

15 Fig. 3 shows the relative position of loop antennæ with respect to the normal course of the vessel, and

20 Fig. 4 illustrates still another modification of this invention.

25 Referring to Fig. 1 of the drawings in greater detail, reference numeral 1 designates a loop antenna connected in series with a winding of 30 the transformer 5 and the variable condenser 9 to the winding 11. The antenna 2 is coupled to the circuit of the loop antenna 1 through the transformer 5. The degree of coupling between the windings of the transformer 5 is adjusted until the desired cardioid field strength characteristic is obtained for the antenna array including the antennæ 1 and 2. Another loop antenna 3 is coupled to the non-directional antenna 4 through the transformer 6. The degree of coupling of the windings of the transformer 6 is adjusted until the cardioid field strength characteristic is obtained for the composite antenna array including antennæ 3 and 4. Variable

35 condensers 1 and 8 are connected into the circuits of antennæ 2 and 4, respectively, to provide 40 means for adjusting the natural period of these antennæ. The inductance 12 and the variable condenser 10 are connected into the circuit of 45 the loop antenna 3. The inductances 11 and 12 are positioned at right angles with respect to 50 each other. Another inductance 13 is arranged to be rotated by the motor 14. The slip rings 55 15 and 16 are connected to the inductance 13.

Connections are provided between brushes engaging the slip rings 15 and 16 and the input circuit of the electron discharge device 17. A variable condenser 21 is connected across the inductance 13 for tuning the circuit thereof to the frequency of the desired signals. A transformer 18 is connected to the output circuit of the electron discharge device 17. A high frequency amplifier, detector and low frequency amplifier 19 is coupled to the electron discharge device 17 through the transformer 18 and to the electron discharge devices 22 and 23 through the transformer 20. A source of low frequency alternating current 24 is provided for the anodes of the electron discharge devices 22 and 23. The resistance 25 is connected across the source 24. The cathodes of the electron discharge devices 22 and 23 are connected to the center of the resistance 25. The windings 27 and 28 are connected to the terminals of the resistance 25. The anodes of the electron discharge devices 22 and 23 are connected to the windings 27 and 28 of the relay 26. The windings 27 and 28 are connected to be energized in opposition so that the magnetic field set up by the current flowing through one of them attracts the armature 29 and closes the circuit of the lamp 31, while the current flowing through the other winding sets up a magnetic flux which repels the armature 29 and causes the circuit of the lamp 30 to be closed. The source of current supply 32 is provided for energizing the lamps 30 and 31.

In operation the antennæ 1, 2, 3, and 4 are mounted upon the aircraft or other vessel employing this invention in such a manner that the loop antennæ 1 and 3 are disposed at an angle with respect to each other. The magnitude of this angle is to a large extent determined by the effect of the structure adjacent to the antennæ 1 and the field strength characteristics of the individual array. Where the characteristic of each of the arrays 1, 2 and 3, 4 is of a greatly elongated cardioidal shape the angle between the loop antennæ 1 and 3 may be as small as 20°.

The motor 14 rotates the inductance 13 in such a manner that this inductance is successively coupled to the inductances 11 and 12. When the inductance 13 is coupled to the inductance 11, that is, when the axis of its turns is parallel to the axis of the turns of the inductance 11, signaling energy intercepted by the antennæ array 1, 2 is impressed upon the input circuit of the electron discharge device 17. When the axes of the inductances 12 and 13 are in line, then signaling energy from the antennæ array 3, 4 is impressed upon the input circuit of the electron discharge device 17.

The alternating current generator 24 is adjusted to generate a current the frequency of which bears a definite relation to the speed of rotation of the inductance 13. This relation is a two-to-one ratio; that is, the inductance 13 completes one revolution during the time interval of two cycles of the anode current. This anode current generator 24 is also adjusted to generate a current having a substantially flat wave characteristic. The maximum amplitude of the current wave should occur at the same time that the inductance 13 is most tightly coupled to one of the inductances 11 and 12.

Signaling energy intercepted by the antennæ systems 1, 2 and 3, 4 is successively impressed upon the input of the electron discharge device 17 and the high frequency amplifier, detector and low-frequency amplifier 19. The input circuit of

the electron discharge device 22 is energized by the signaling energy intercepted by, for example, the antenna system 1, 2. Any signaling energy intercepted by this antenna system 1, 2 will, therefore, be impressed most efficiently upon the input circuit of the discharge device 17 when the coupling coefficient between the coils 11 and 13 is maximum. It is, therefore, of course, essential that the anode circuit of the discharge device 22 is energized at the same time as the coefficient of coupling between the coils 11 and 13 is going through the maximum portion of its cycle. If the signaling energy intercepted by the antennæ 1, 2 is of sufficient strength the winding 27 of the relay 26 will be energized and the circuit of the lamp 31 closed, whereupon the lamp 31 will flash or remain luminous during the interval of time during which the input or anode circuits of the discharge device 22 are energized. The lamp 31 will, of course, cease to remain incandescent upon the decrease of the energization of either the input or anode circuits of the discharge device 22. As the inductance 13 is rotated and passes through the portion of its cycle during which the coupling between it and the coil 12 is maximum any signaling energy of the proper frequency intercepted by it will be impressed upon the circuits of the amplifier arrangement and through the operation of the discharge device 23, the anode circuit of which is simultaneously energized, the winding 28 of the relay 26 is energized, and if the signal intercepted is of sufficient strength the circuit of the lamp 30 is closed, whereupon the lamp 30 becomes temporarily incandescent. When the antennæ 1, 2 and 3, 4 intercept signaling energies of the same, or substantially the same, magnitude the lamps 30 and 31 will flash alternately. When the signaling energy intercepted by one of the antenna arrays is substantially greater than that intercepted by the other, then only one of the lamps will flash. The operator of the system is informed that the aircraft is proceeding in a normal course indicated by *x* (Fig. 3) to the airport when the lamps flash alternately.

In Fig. 2 of the drawings a modified form of this invention in which three directional antenna arrays 41, 42 and 43, disposed at small angles with respect to each other, are employed for successively impressing signaling energy upon the input circuit of the electron discharge device 44. These antennæ 41, 42 and 43 may be made up of arrays similar to those illustrated in Fig. 1. Three electron discharge devices 45, 46 and 47 are coupled to the discharge device 44 through the high frequency amplifier, detector and low frequency amplifier arrangement 49 and the transformer 50. The secondary of the transformer 50 is divided into three independent windings 50a, 50b and 50c which are connected to the input circuits of the electron discharge devices 47, 46 and 45, respectively.

A polyphase generator 48 is provided to energize the anode circuits of the devices 45, 46 and 47. The phase *a* is connected thru the winding 45a of relay 49 to the anode of the device 45. The phase *b* is connected thru the winding 46a to the anode of device 46. The anode current of device 45 flows thru winding 45a in the opposite direction to that in which the anode current of device 46 flows thru the winding 46a. The relay 49 is provided with an additional winding 50. The center of the winding 50 is connected thru the variable resistance 51 and the rectifier 52 to the neutral slip ring of the generator 48. The termi-

nals of the winding 50 are connected to the phases *a* and *b* in such a manner that the magnetizing effect of the normal anode currents of the electron discharge devices 45 and 46 will be neutralized by the magnetic force set up by the two sections of the winding 50. The effect of the winding 50 may be regulated by varying the current flowing therethru so that the magnetic effect of the normal anode currents flowing thru the windings 45 and 46 is not completely neutralized. The relay 49 may thus be regulated to operate upon signals of very low intensity. The anode of the electron discharge device 47 is connected to the phase *c* thru the winding 47a of the relay 53. The winding 55 is also connected to the phase *c* and is connected in opposition to the winding 47a so that the magnetic field set up by the anode current flowing thru this latter winding may be either partially or wholly neutralized. The variable resistance 54 is provided to control the current flow thru the winding 55.

The inductances 71, 72, and 73 are connected to the antennæ 41, 42 and 43, respectively. These inductances are angularly displaced with respect to each other. The inductance 74 is rotatably mounted upon a bearing 78 so that in one revolution it is successively coupled to each of the inductances 71, 72 and 73. The inductance 74 is connected to the slip rings 75 and 76. Brushes associated with these slip rings are connected to the input circuit of the electron discharge device 44.

In operation the inductance 74 is successively coupled to inductances 71, 72 and 73 which are connected to the antennæ 41, 42 and 43, respectively. Signaling energy intercepted by these antennæ is thereby impressed upon the circuits of the amplifier. The anode circuits of the electron discharge devices 45, 46 and 47 are successively energized thru the operation of the poly-phase generator 48. The cycle of energization of these electron discharge devices is adjusted in duration so that the signaling energy intercepted by the antenna 42 is impressed upon the circuit of the amplifier through the operation of the inductances 72 and 74 when the anode circuit device 46 is being energized. If signaling energy of sufficient intensity is being intercepted during this interval, then the lamp 58, the circuit of which is controlled by the energization of the winding 46a of the relay, is caused to flash. When this lamp flashes periodically, then the operator is informed that the aircraft is on the normal course. Signaling energies intercepted by the antennæ 41 and 43 are impressed upon the amplifier circuits during the interval of time when the anode circuits of the electron discharge devices 45 and 47 are being energized. If the aircraft deviates either to the left or right of its normal course, then one of these antennæ will intercept signaling energy and one of the relays 49 or 53 will operate to intermittently close the circuit of one of the lamps 57 or 60. The armatures 56 and 61 of the relays are polarized. The armature 56 may be held in neutral position by small springs. The source of current supply 62 is provided for the lamps 57, 58 and 60.

In Fig. 4 a modified form of this invention is illustrated in which the motor 70 is employed to oscillate the contacting arm 71 of the resistance 72 back and forth and simultaneously rotate the inductance 73 which corresponds to the inductance 13 of Fig. 1. As the arm 71 is oscillated back and forth the anode circuits of the electron discharge devices 74 and 75 are successively en-

ergized. A constant source of current supply 76 may thus be employed in the place of the alternating source 24 of Fig. 1.

While I have described this invention in considerable detail, it is, of course, understood that various detailed modifications thereof may be made without departing from the scope or spirit thereof, and that, therefore, I do not desire to limit this invention to the exact details as set forth except in so far as those details may be defined by the appended claims.

What I claim and desire to secure by Letters Patent of the United States is:

1. In directional radio receiving systems, the combination of a plurality of directional antennæ adjusted to receive signaling energy of maximum intensity from different directions, amplifying means, means for successively coupling said antennæ to said amplifying means, a relay having a plurality of windings, a plurality of electron discharge devices connected to the output of said amplifying means, different ones of said relay windings being connected to the anode circuits of different ones of said electron discharge devices, means for periodically varying the energization of said anode circuits simultaneously as different ones of said antennæ are coupled to said amplifying means whereby selected ones of said relay windings are energized in accordance with signals intercepted by different ones of said antennæ.

2. In directional radio receiving systems, the combination of a plurality of directional antennæ adjusted to receive signals of maximum intensity from different directions, amplifying means, means for successively coupling said antennæ to said amplifying means, a relay having a plurality of windings, a pair of electron discharge devices connected to said amplifying means, connections between one of said electron discharge devices and one of said windings, connections between the other of said electron discharge devices and another of said windings, means for periodically energizing said windings in accordance with signaling energy and means for operating said last mentioned means in step with said second mentioned means.

3. In directional radio receiving systems, the combination of a plurality of means for intercepting signaling energy from different directions, amplifying means, means for coupling said signal intercepting means to said amplifying means, means for periodically varying said coupling means, a pair of electron discharge devices connected to said amplifying means, a relay having a plurality of windings, one of said windings being connected to one of said electron discharge devices and another of said windings being connected to another of said electron discharge devices, means for periodically varying the energization of said windings, said last mentioned means being operated in a definite time relation with said coupling varying means.

4. In directional radio receiving systems, the combination of a plurality of means for intercepting signaling energy from different directions, amplifying means, means for coupling said signal intercepting means to said amplifying means, means for periodically varying said coupling means, a pair of electron discharge devices connected to said amplifying means, indicating means, electro-magnetic means having a plurality of windings for controlling said indicating means, connections between one of said windings and one of said electron discharge devices, connections

between another one of said windings and the other of said electron discharge devices, means for periodically varying the energization of said windings in time relation with said coupling varying means whereby different ones of said windings are energized in accordance with signaling energy intercepted from different directions.

5. In directional radio receiving systems, the combination of means for intercepting signaling energy from a plurality of different directions with maximum amplitude, amplifying means, means for coupling said signal intercepting means to said amplifying means, means for varying said coupling means whereby said amplifying means is energized in accordance with signaling energy intercepted from different directions periodically, electro-magnetically controlled indicating means having a plurality of windings, a pair of electron discharge devices connected to said amplifying means, connections between one of said electron discharge devices and one of said windings, connections between the other of said electron discharge devices and another of said windings, means for alternately rendering said electron discharge devices operative whereby said windings are alternately energized in accordance with signaling energy and means for operating said last mentioned means in definite time relation with said coupling varying means.

30. 6. In directional radio receiving systems, the combination of amplifying means, means for successively impressing signaling energy intercepted from one of several different directions upon the input circuit of said amplifying means, electron discharge device means having a pair of anode circuits connected to said amplifying means, indicating means, electro-magnetic means for controlling the operation of said indicating means, said electro-magnetic means having a plurality of windings, connections between one of said windings and one of said anode circuits, connections between another one of said windings and the other of said anode circuits, means for alternately energizing said anode circuits and means for

operating said last mentioned means and said second mentioned means in time relation whereby different ones of said windings of said electromagnetic means are energized in accordance with signaling energy intercepted from different directions.

7. In directional radio receiving systems, the combination of amplifying means, rotatable means for successively impressing signaling energy intercepted from different directions upon the input circuit of said amplifying means, electron discharge device means having a pair of anode circuits connected to said amplifying means, indicating means, electro-magnetic means having a plurality of windings for controlling said indicating means, connections between one of said anode circuits and one of said windings, connections between the other of said anode circuits and another of said windings, means for periodically energizing said anode circuits and means for operating said last mentioned means in time relation with said rotatable means.

8. In directional radio receiving systems, the combination of amplifying means, a plurality of means for intercepting signaling energy from different directions, means for coupling said signal intercepting means to said amplifying means, means for periodically varying the effect of said coupling means upon said amplifying means, electron discharge device means connected to said amplifying means, said electron discharge device means having a pair of anode circuits, indicating means having a plurality of windings, connections between selected ones of said windings and said anode circuits, means for periodically varying the energization of said anode circuits and said windings, means for operating said last mentioned means in definite time relation with said means for periodically varying the effect of coupling whereby different ones of said windings are energized in accordance with signaling energy intercepted by different ones of said signal intercepting means.

BEN J. CHROMY.
